UNITED STATES PATENT OFFICE.

OSCAR S. NEWCOMB, OF HESPERIA, MICHIGAN.

DRAG-SAW.

SPECIFICATION forming part of Letters Patent No. 310,075, dated December 30, 1884.

Application filed March 15, 1881. (No model.)

To all whom it may concern:

Be it known that I, OSCAR S. NEWCOMB, a citizen of the United States of America, residing at Hesperia, in the county of Oceana and State of Michigan, have invented certain new and useful Improvements in Wood-Sawing Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to log-sawing machines; and it consists in the improvements hereinafter fully described and set forth.

In the accompanying drawings, forming part of this specification, Figure 1 is a side view of 20 a sawing-machine constructed in accordance with my invention. Fig. 2 is a plan view of Fig. 1, parts being removed. Fig. 3 is a longitudinal section, and Fig. 4 is a front elevation.

The frame of the sawing-machine consists of 25 side bars, A, and front and rear end bars, B. Standards C are secured centrally on the upper sides of the side bars, A, and are perforated for the passage of a shaft, a, having its ends bent to form crank-handles, *a'*. The said shaft *a* has keyed thereon a pinion, b, and has loosely 30 thereon a hub or sleeve, c, from which extends an arm, D, provided with a slot, d, at its lower end, and transversely perforated thereat. An arm, E, integral with the arm D, extends at 35 right angles from the central portion of said arm D, as shown in Fig. 3. A sleeve, F, turns on a shaft, e, which bears at its ends in the upper portions of the standards C. Integrally 40 extending rearwardly from the center of said sleeve F is an arm, G. A shaft, f, is journaled in the rear portion of the side bars, A, and is bent at its center to form a crank, g. A rod, H, connects the crank *g* with the rear extremity of the arm G. A connecting-bar, H', is 45 pivotally attached at one end to the center of the arm G, and at its other end to the extremity of the arm E. The said connecting-bar H' is composed of two independent sections, *h h'*, each of which is provided with a shoulder, *h*, 50 *h'*, against which the end of the other section bears. Each of said sections is provided with

an elongated slot registering with one another, and through these slots pass one or more bolts, *i*, on the threaded ends of which engage clamp-nuts *j*, which secure said sections *h h'* together, 55 but permit their longitudinal adjustment with respect to each other, so as to effect the extension of the bar H'. The crank-shaft *f* has keyed thereon at one side thereof a pinion, k, and upon the projecting end of the said crank-shaft 60 is keyed the fly or balance wheel. A train of gear-wheels, *l l'*, convey motion from the pinion *b* on the shaft *a* to the said pinion *k*.

Bearing loosely on the end of the shaft *m* of the pinion *l* is a lever, L, carrying at one end 65 a brake-shoe, M, which can, when desired, be applied to the periphery of the wheel to retard the movement thereof. A shaft, *n*, bearing in brackets is secured at the under side of the frame, and carries a pinion, N, which meshes 70 with the teeth of the pinion *l*. The said shaft carries a band-pulley at one side, by which the machine can be readily belted to be driven from any suitable motor. The front portions of the bars A and extensions of the standards C 75 are curved to form yoke-arms O O', connected to each other by means of vertical rods *o*, which pass through and serve as guides for horizontal bars *p*, connected together by means of parallel vertical bars *q*, in which are journaled 80 rollers *r*, between which play the edges of the smooth portion of a saw-blade, P, pivotally connected at the lower end of the bar D. An iron or rod, *s*, is secured pivotally at each end to the outer side of the bars *q*, and is bent in 85 the form of an inverted yoke, *t*, at its front end to rest on the saw-blade P and prevent lateral play of the same. A loop, *u*, located centrally on the upper side of the bar *p*, has attached thereto a cord, *v*, which passes up over pulleys 90 *w*, located in the bar O, and hangs pendent from one side of the same, and carries a loop by which it can be pulled to elevate the saw-guiding frame formed by the bars *p q*. A metallic handle, S, is provided with bifurcated 95 extensions *x*, through which passes one of the rods *o*, the said extensions being located immediately between the ends of the bars *p*, as shown in Fig. 4, so that by manipulating said handle S the saw-guide frame can be elevated 100 thereby independent of the cord *v*.

The operation of the machine will be obvi-

ous. Suffice to say that the various drive and gear connections rotate the crank-shaft *g*, thereby intermittently elevating and depressing the connecting-arm *H*, vibrating the shaft *G*, and 5 horizontally reciprocating the saw *P* by means of the arm and bar connection *D E*.

The operation and purpose of the devices located at the front of the machine have already been explained.

10 By adjusting the nuts and bolts that secure the sections *i i'* together the connecting-bar *H'* connected thereby may be readily increased or decreased in length, so as to vary the vibration imparted to the arm and bar *D E*, and 15 consequently the reciprocating movement of the saw.

I am aware that previous to my invention it has been proposed to employ adjustable extensible levers connected directly to the saw- 20 blade, and operated directly by a handle connected to said lever, and, further, that crank mechanism and gear of various styles for driving saw-blades are old. Moreover, I am con- 25 versant with certain prior patents wherein saw supporting and guiding frames are described and illustrated. I therefore make no broad claim to any of these features.

I claim—

1. The combination, in a sawing-machine, of a frame, saw devices supported and operating 30 therein, crank mechanism carried by said frame, gear-wheels mounted upon shafts bearing in said frame and operated by said crank mechanism, a bar connecting said saw devices and gear-wheels, and composed of independent 35 sections secured by bolts, each section being longitudinally adjustable with respect to the other, so that the movement of the saw can be regulated without varying the speed of the driving-gear, substantially as set forth. 40

2. The combination, in a sawing-machine, of an angle-arm, *D E*, hung loosely on a shaft, a series of multiplying gear-wheels connected adjustably to said angle-arm by an extensible arm, *H'*, and a saw guided at the front of the 45 machine in a vertically-adjustable frame containing rollers *r r*, for the purpose described, and connected to the angle-bar, substantially as set forth.

In testimony whereof I affix my signature in 50 presence of two witnesses.

OSCAR S. NEWCOMB.
